UNITED STATES PATENT OFFICE

171,843

FLOWER BOWL

Natalie de Lebecque, Beverly Hills, Calif.

Application April 2, 1953, Serial No. 24,323

Term of patent 3½ years

(Cl. D35—3)

To all whom it may concern:

Be it known that I, Natalie de Lebecque, a citizen of the United States of America, residing in the city of Beverly Hills, county of Los Angeles, State of California, have invented a new, original, and ornamental Design for a Flower Bowl, of which the following is a specification, reference being had to the accompanying drawing, forming a part thereof.

I claim:

The ornamental design for a flower bowl, substantially as shown.

NATALIE DE LEBECQUE.
